Des. 204,272
Patented Apr. 5, 1966

204,272

PAINTER'S EASEL

Orville Bulman, Grand Rapids, Mich., assignor to The
E. O. Bulman Manufacturing Company, Inc., Grand Rapids, Mich., a corporation of Michigan

Filed Apr. 7, 1965, Ser. No. 84,648

Term of patent 14 years

(Cl. D29—20)

Fig. 3

I claim:

The ornamental design for a painter's easel, as shown and described.
